DRAWER PULL HANDLE

John E. Fellowes, Wheaton, Ill., assignor to
Bankers Box Company, Chicago, Ill., a corpora-
tion of Illinois

Application February 27, 1953, Serial No. 23,825

Term of patent 14 years

(Cl. D10—8)

To all whom it may concern:

Be it known that I, John E. Fellowes, a citizen of the United States and resident of Wheaton, in the county of Du Page, and State of Illinois, have invented a new, original, and ornamental Design for a Drawer-Pull Handle, of which the following is a specification, reference being had to the accompanying drawing, forming a part hereof.

Fig. 1 is a perspective view taken from in front and to one side of a drawer-pull handle embodying my new design;

Figs. 2, 3 and 4 are respectively front elevational, side and top plan views of the drawer-pull handle shown in Fig. 1;

Figs. 5, 6 and 7 are fragmentary top sectional views taken substantially on lines 5—5, 6—6 and 7—7 of Fig. 2 respectively, to show details of the variations in contours of a portion of the structure;

Fig. 8 is a fragmentary end sectional view taken substantially on a line 8—8 of Fig. 2, and in the

direction of the arrows, to illustrate a detail of the structural shape; and

Fig. 9 is a fragmentary top sectional view taken substantially on a line 9—9 of Fig. 2, and in the direction of the accompanying arrows to indicate another detail of the contours of the illustrated drawer-pull handle.

The characteristic features of the design reside in the solid line portion.

I claim:

The ornamental design for a drawer-pull handle, substantially as shown and described.

JOHN E. FELLOWES.
